UNITED STATES PATENT OFFICE.

RAYMOND T. BROWN, OF LIMA, OHIO.

WRENCH.

1,420,409.

Specification of Letters Patent. Patented June 20, 1922.

Application filed July 20, 1921. Serial No. 486,191.

To all whom it may concern:

Be it known that I, RAYMOND T. BROWN, a citizen of the United States, residing at Lima, in the county of Allen and State of Ohio, have invented certain new and useful Improvements in Wrenches, of which the following is a specification.

This invention relates to wrenches and has for its object the provision of simple, inexpensive and efficient means whereby the movable jaw of a wrench may be quickly and easily set at the proper point upon the shank to engage a nut of any dimensions. A secondary object of the invention is to eliminate the adjusting screws and nuts which are now ordinarily employed to adjust the movable jaw, and a further object of the invention is to provide a construction in which the movable jaw may be removed entirely from the shank if such removal should be desirable for any purpose.

The invention is illustrated in the accompanying drawings, in which—

Figure 1 is a side elevation of a wrench embodying one form of my invention;

Fig. 2 is a view, partly in side elevation and partly in longitudinal section;

Fig. 3 is a transverse section on the line 3—3 of Fig. 2;

Fig. 4 is a detail perspective view of the holding dog.

In carrying out my invention, I employ a shank 1 which may be of the usual flat-sided formation and has the fixed jaw 2 formed upon one end, the jaw being shown in the present instance as at an angle of about 60° to the shank so that the wrench will accommodate a hexagonal nut. It is to be understood, however, that the jaw may be at a right angle to the shank or otherwise disposed so that a nut of any design may be engaged. In that edge of the shank which merges into the fixed jaw, I provide a series of transverse teeth 3 which cooperate with a holding dog upon the movable jaw to hold the movable jaw in a set position. The movable jaw comprises a sleeve or tubular body 4 of proper form and dimensions to slidably fit upon the shank and from one side of this tubular body the jaw 5 extends at an angle to the sleeve or tubular body corresponding to the angle of the fixed jaw 2, as clearly shown. At the base of the jaw 5, a transverse opening or recess 6 is formed in the body 4 and the holding dog 7 is adapted to play in this recess, being provided with for-

wardly extending lugs or perforated ears 8 which extend alongside the movable jaw, as shown clearly in Fig. 1, and are pivoted thereto by a pin or rivet 9 inserted through said lugs or ears and the movable jaw as will be readily understood. The inner side or edge of the dog is provided with transverse teeth 10 adapted to engage the teeth 3 on the shank and interlock therewith so that the resistance of the nut to the jaw will be transmitted to the teeth and the jaw thereby held in working engagement with the nut when the wrench is manipulated to turn the nut home or retract it in an obvious manner. Secured to the outer side of the dog 7 is a bracket or finger piece 11 and a coiled spring 12 is disposed between the said finger piece and the base of the jaw 5 and received within a socket 13 formed in said jaw, as clearly shown in Fig. 2. It is also to be noted that the surface of the movable jaw opposed to the forward end of the dog is tapered or made convex concentric with the pivot 9, as shown at 14, to readily accommodate the swinging movement of the dog in the manipulation of the tool.

When the wrench is to be used, the dog is released from the teeth 3 of the shank by slight pressure upon the thumb piece 11 and the movable jaw may then be slid easily longitudinally of the shank so that it will be brought into engagement with the nut. When the nut is closely engaged by and between the jaws, the thumb piece is released and the spring 12 will then immediately expand and swing the dog into engagement with the teeth on the shank so that the nut will be firmly held and turning movement applied to the wrench will be transmitted directly to the nut. It will be readily noted that my wrench is very simple in the construction and arrangement of its parts and, obviously, the movable jaw may be set to accommodate a nut of any given size in a very small fraction of time.

Having thus described the invention, what is claimed as new is:

A wrench comprising a shank having a fixed jaw at one end and provided in one edge with a longitudinal series of transverse teeth, a movable jaw having a sleeve portion slidably fitted upon the shank, said sleeve portion being provided with a transverse opening in one side at the base of the jaw, a holding dog pivotally attached to the movable jaw at the base of the same and in ad-

vance of the opening and playing in said opening and provided in one edge with transverse teeth to engage the teeth on the shank, the movable jaw having a socket in its rear side spaced outwardly from the pivot of the dog, a finger piece projecting laterally from the holding dog across the

socket in the movable jaw, and a coiled spring bearing at one end against the front side of the finger piece and having its opposite end housed in the socket in the movable jaw.

In testimony whereof I affix my signature.

RAYMOND T. BROWN. [L. S.]
